ARTICLE SURFACING MACHINE

Richard F. Kneisley, Toledo, Ohio, assignor to
 Kneisley Electric Company, Toledo, Ohio, a
 partnership

Application May 16, 1945, Serial No. 594,024

3 Claims. (Cl. 51—50)

1

This invention relates to machines for grinding and truing the surfaces of tubular or cylindrical members, and is particularly adapted and intended for operation on short tube lengths of rubber, or other plastic material.

The primary object of the invention is the provision of a simple and efficient machine of this character which will simultaneously operate on a plurality of work-pieces to not only grind or abrade the surfaces thereof, but also to render them uniform as to diameter and surface configuration.

Further objects and advantages of the invention will be apparent from the following detailed description of the invention and from the accompanying drawings illustrating one embodiment thereof, in which

Fig. 1 is a side elevation of a machine embodying the invention, with the grinding wheel near the left end of its stroke; Fig. 2 is a vertical cross-section on the line 2—2 in Fig. 1; Fig. 3 is a similar section on the line 3—3 in Fig. 1; Fig. 4 is a fragmentary sectional detail on the line 4—4 in Fig. 2, and Fig. 5 is an enlarged sectional detail on the line 5—5 in Fig. 2, with parts in full, and Fig. 6 is a diagram of the wiring.

Referring to the drawings, 1 designates a substantially flat table or frame supported by standards 2 and carrying the operating parts of the machine. Fixedly mounted on the top of the table 1 near one end on standards 3 is a pair of axially spaced disks 4 held apart and braced by a plurality of tie-rods 5, eight in the present instance, which are equidistantly spaced in concentric relation around the axis of the disks. Carried by the disks 4, with one midway between each pair of adjacent rods 5, is a set of work-carrying spindles 6 and 7, the former being the live spindle and the other the dead spindle. These spindles are provided at their adjacent ends with conical centers 8 for engaging the respective ends of a work-carrying mandrel 9 for concentric turning therewith. The dead or tail spindle 7 is adapted to have limited axial movements in a sleeve 10 carried by the respective disk 4 and is held in yielding center engagement with the mandrel by the action of a coiled expansion spring 11. The live spindle is provided with a radially projecting pin 12 which engages an L finger 13 projecting from the adjacent end of the mandrel 9 and causing the mandrel to turn with the spindle. The finger 13, in the present instance, is carried by a collar 14 that is held in adjusted position thereon by a set-screw.

2

15. A work-piece 16 of tubular form is mounted on the mandrel 9 with a sufficiently tight fit to frictionally turn therewith. This work-piece, which constitutes a short length of tubing of soft rubber or plastic material, is mounted on and removed from the mandrel 9 at the tail-piece end thereof before engagement of the mandrel between the centers 8.

10 The several work-pieces 16, when mounted on the mandrels 9 and held in working position by the sets of spindle centers 8, are disposed in circular series concentric to the axes of the disks 4 in position to be circumferentially engaged by the peripheral surface of an abrading wheel 17, 15 that is rotatably mounted within the annular space defined by the work-pieces, as hereinafter described.

10 The several spindles 6 are driven in unison by a chain 18 extending around spindles 19 on the outer ends of the spindles, and this chain, between two of said sprocket wheels, extends over a drive sprocket wheel 20 on a drive shaft 21. This shaft is journaled in standards on a bracket 22 which is mounted on the left end portion of the table 1 for vertical adjustment to tighten or slacken the chain 18. In the present instance, a motor 23 for driving the shaft 21 is attached to the under side of the adjacent end portion of the table 1 and has a suitable belt and pulley driving connection 24 with said shaft.

30 The abrading wheel 17, which is preferably of a nature to grind and reduce the surfaces of the member 16 so as to render them of uniform diameter, is mounted on a shaft 25 projecting from and driven by the rotor member of a motor 26, and disposed centrally of the set of mandrels 9. This shaft extends beyond the abrading wheel 17 and is mounted at each side of such wheel in bearings 27 within tubular housing sections 28, the inner one of which relative to the motor 26 is fixedly attached to the motor housing. These housing sections project through center bearing openings 29 in the disks 4 and the outer one is prevented from turning with the shaft by a feather 30 thereon engaging a recess in the opening wall of the respective disk.

35 The motor 26 is mounted on a carriage 32 for axial movements toward and away from the adjacent disk 4. This carriage is mounted on a track 33 supported by the table 1. A feed-screw 34 fixedly projects from the outer or right hand end of the housing of the motor 26 through the hub of a pulley 35 in threaded engagement therewith. This pulley is suitably mounted in standards 36 rising from the table 1 and held thereby

against axial movements so that rotation of the pulley will impart axial movement to the motor 26 through the medium of the feed-screw 34. It is apparent that such movement of the motor 26 will shift the shaft 25 and the housing sections 28 with respect to the disks 4 so that the abrading wheel is caused to have axial movements in parallel relation to the axes of the work-carrying mandrel 9. The pulley 35 is driven from a motor 40 suspended from the bottom of the right end portion of the table 1, such driving being through a pulley and belt connection 41 to a countershaft 42, and thence from a pulley on said shaft and belt 43 to the feed-screw pulley 35. The motor 40 is of the reverse type so as to drive the feed-screw 34 in either direction as desired, and is controlled by a reversing switch 45 of which 46 is the control handle.

When the carriage 32 is at the limit of its movement to the left, an arm 47 thereon engages the control button of a normally closed limit switch 48 and opens the motor control circuit, and when at the limit of its travel to the right an arm 47' thereon engages the control button of a normally closed limit switch 49 and again opens said motor control circuit. Since the operation of the travel motor 40 is controlled by limit switches, normally open shunting switches 50 and 51 are provided in parallel with the respective switches 48 and 49 to be selectively closed during starting of the travel motor to return it in the opposite direction. Thus, to accomplish its return, the control arm 46 of the reversing switch 45 is thrown in the opposite direction after which the respective shunt switch 50 or 51, is normally held closed until the carriage has started and moved sufficiently in the opposite direction to effect release of the limit switch; when the shunting switch may be released. It is apparent that the carriage 32 and grinding wheel 17 come to rest at each end of their strokes and remain at rest until the reversing switch 45 has been thrown and the respective shunt switch 50, 51, closed.

In the wiring diagram shown in Fig. 6, a three-wire main line circuit having wires *a*, *b*, and *c*, is employed, and leads *d*, *e*, and *f* extend from these to the several motors 23, 26 and 40. A main control switch 53, common to all the motors, is disposed in these leads and the reverse switch 45 is disposed in two of the branch leads to the travel motor 40. The motor switch 53 is of the normally open electro-magnet type, with its solenoid coil 54 disposed in the control circuit *g* in which the two limit switches 48 and 49 are disposed, so that when either of said limit switches, or a control switch 55, in the circuit *g*, is open the coil is deenergized so that the motor control switch 53 is open and the motors are at rest.

In the operation of the machine, the grinding of the work-pieces occurs during axial travel of the grinding wheel in one direction or the other and when the wheel travel is at rest at each end of its stroke, the mandrels are removed with the ground work-pieces thereon to permit removal of such pieces from the mandrels. When this has been done and other work-pieces placed on the mandrels, the latter are replaced in connection with the spindles 8 and the button of the shunt switch 50, 51, associated with the limit switch that is then open, is pressed to close the motor control circuit *g* and to retain it closed until the carriage 32 is moved sufficiently in its reverse direction to release the engaged limit switch button. The carriage then continues its travel

movement until the opposite limit switch has been engaged and opened to effect an opening of the motor control switch 53 and a stopping of the travel of the grinding wheel at the opposite end of its stroke, removal of the ground work-pieces and substitution of others on the mandrels may again be repeated.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. In a machine of the class described, a mandrel mounted for rotary movements and adapted to hold an axially elongated cylindrical work-piece, means including an electric motor for rotating said mandrel and work-piece, a carriage mounted for reciprocatory movements in a plane parallel to the axis of rotation of the mandrel, an electric motor mounted on said carriage for movement therewith, a grinding wheel driven by said last motor for peripheral engagement with a side of the work-piece carried by the mandrel and for movement with the motor to cause the wheel to traverse from one end to the other of the work-piece, feed means including an electric reversing motor for imparting predetermined movement to said wheel, first motor and carriage lengthwise of a work-piece, said electric motors being connected in a common electric circuit, a normally open main switch in said circuit, a control circuit including means magnetically operable to maintain said switch closed when said control circuit is closed, a control switch and two normally closed limit switches in said control circuit, means movable with said carriage for opening one or the other of said limit switches when the carriage is at one or the other end of its intended reciprocatory movement, a normally open shunt switch in said control circuit in association with each limit switch and operable to close the control circuit during an open period of the associated limit switch, and a manually operable reversing switch in circuit with said reversing motor.

2. In a machine of the class described, a plurality of mandrels each for holding a tubular work-piece, means for releasably holding said mandrels in circular series with their axes parallel and for rotating each mandrel about its axis, an abrading wheel mounted within the series of mandrels concentric thereto for peripheral trimming engagement with a work-piece carried by each mandrel, an electric motor operable to rotatably drive said wheel, a feed means operable to impart axial movements to said wheel to move it lengthwise of the work-pieces, a second motor for driving said feed means, an electric circuit including said motors, a normally open electro-magnet switch for closing said motor circuit, and an electric control circuit operable when closed to effect a closing of said switch and including a normally closed limit switch that is automatically operable to open said control circuit at a predetermined point in an axial movement of said wheel and its driving motor.

3. In a machine of the class described, a mandrel for holding and rotating a cylindrical work-piece, means including an electric motor for driving said mandrel, a grinding wheel mounted for axial reciprocatory travel and to have peripheral grinding coaction with the surface of the work-

piece during such travel, an electric drive motor for said wheel axially movable therewith, means including an electric reverse motor for imparting axial reciprocatory movements to said wheel and its driving motor, an electric circuit common to all of said motors, a normally open magnetic switch in said circuit, a control circuit for said switch operable when closed to maintain said switch in closed position, a manually controlled reversing switch in circuit with said reverse mo-

10

tor, two normally open limit switches and a control switch in said control circuit, means movable with said wheel and its motor during axial travel thereof to engage and open one or the other of said limit switches at the end of each stroke of said wheel and its motor, and means associated with each limit switch and manually operable to close the control circuit during an opening thereof by the associated limit switch.
